WATER TUBE BOILER

Filed May 8, 1926

INVENTOR

Alfred C. Danko,
by
James C. Bradley

UNITED STATES PATENT OFFICE.

ALFRED C. DANKS, OF CLEVELAND, OHIO.

WATER-TUBE BOILER.

Application filed May 8, 1926. Serial No. 107,607.

The invention relates to water tube boiler constructions, and particularly to the vertical types, known as the Stirling and Connelly, Heine and others. The best known of these boilers employ a bottom drum and three spaced upper drums with a set of tubes extending from the bottom drum to each upper drum, but in some cases, there are only two upper drums and two banks of tubes. The invention has to do primarily with the baffle arrangement, which involves a radical departure from the established practice in boilers of the vertical type. Heretofore, it has been customary to arrange the baffles, so that the gases of combustion in the various banks of tubes travel, in the main, longitudinally, and therefore, parallel to the tubes, making relatively sharp bends adjacent the ends of the tube banks. In the present construction, the baffles are so arranged so that the gases of combustion cross the various banks of tubes at substantially right angles thereto. This arrangement reduces the sharpness of the reversals or bends which the gases of combustion must make, in moving from one pass to the next, and thus improves the draft conditions. The arrangement also results in an increase in area of the available heating surface in the first and second passes where the temperatures are higher, thus increasing the heat absorbing capacity of the apparatus and reducing stack temperatures. A further feature of construction, involving a departure from previous practice, and giving a higher efficiency, is the arrangement of the baffles so that the net cross sectional area in the passes from the first to the last gradually decreases, following in a measure, the law of contracting gases due to cooling. The velocity of the gases is thus prevented from being reduced, as would otherwise be the case, if the reduction in cross sectional area did not occur, and I have found that this feature of construction, tending to prevent any reduction in the velocity of transit of the gases throughout the heating passage-way of the boiler, adds substantially to its efficiency. A further object attained is a larger net area or clearance space between the tubes at the various passes, such areas being in all cases greater than the damper areas so that the draft losses at the passes is reduced to a minimum. One embodiment of the invention is illustrated in the accompanying drawing, wherein:

The figure is a vertical section through a water-tube boiler constructed in accordance with my invention.

Referring to the drawing, 1, 2 and 3 are the upper drums of the boiler, and 4 is the lower drum, such drums being connected by the three banks of tubes 5, 6 and 7. The upper drums are connected by the usual sets of tubes 8 and 9.

In the particular construction shown, the boiler is fired with gas by means of the burners 10, 10, which direct the gas from the main, mixed with air into the fire-box 12, but it will be understood that the boiler may be provided with the usual hand fired grates or with automatic stokers located, either on the left hand side of the setting, or on the right hand side, and fired with powdered coal or oil, the invention not being limited as to this detail of construction, although the one shown is preferred. Following the usual practice, the side of the construction on which the gases of combustion first pass the tubes, will be referred to as the front side, and the other side (left), on which the outlet flue 14 is located will be referred to as the rear side, the banks or sets of tubes and drums being correspondingly designated. The space 12 into which the burners are directed, will be referred to as the fire-box, although the space 11 to the right, is in a measure a continuation of such fire-box, the upper side being formed by the fire brick arch 13. The space above the arch 13 leads upwardly to the outlet flue or stack 14.

The flow of the gases of combustion across the banks, or sets of fire tubes 7, 6 and 5 is governed and directed by a pair of baffles, which constitute an important feature of my invention. The right hand baffle is made up of two sections, the lower section 15 extending longitudinally of the tubes 7, while the upper section 16 extends transversely of the tubes 7 and 6, so that the gases of combustion sweep across the upper portions of both banks of tubes before they recurve and flow downwardly and to the rear.

The left hand baffle comprises an upright section 17 extending longitudinally of the upper portion of the bank of tubes 5, and an inclined section 18 which extends transversely of both banks of tubes 5 and 6. The gases of combustion after recircling around the upper end of the section 16, and across the upper ends of a part of the tubes 5, flow

downwardly and to the right across both sets of tubes 6 and 7, after which they turn to the left again, passing across the tubes 6 and 5 and upward to the stack. The baffles are 5 preferably composed of suitable reinforced plastic material and extend continuously across the entire setting.

The baffles are preferably arranged so that the net areas at A, B, C, D and E provide 10 an orifice or passageway for the gases of combustion, which gradually decreases in cross section, corresponding approximately to the decreased volume of the gases incident to their shrinkage in cooling. The velocity 15 of the gases throughout the passageway is, therefore, maintained substantially constant, or speeded up somewhat, which is a condition found to give improved efficiency as compared with a condition in which the velocity of the gases slows down as they progress through the various passes. The net cross sectional areas of the passes, as compared with the damper area, is such that proper draft is insured.

20 The advantages incident to the baffle arrangement has been already set forth, heretofore, and include improved draft conditions and increased heat absorbing qualities, so that the arrangement materially increases 25 the rating of boilers to which they are applied. The bends at the ends of the passes are also more gradual, and there are no contractions in cross sectional area in the various passes to a point below that of the damper or flue area, or any dead spaces in 30 which gases are not in motion, so that the draft conditions are favorable. The available heating surface in the first and second passes, where the temperatures are highest 35 is relatively large as compared with previous arrangements, which increases the heat absorbing capacity of the boiler and gives lower stack temperatures. The gradually decreased cross sectional area of the conduit 40 or passageway for the gases of combustion also results in improved economy of operation for the reason heretofore pointed out. There are no spaces for the collection of soot, 45 which are not readily accessible, and the baffle cost is far below that incident to baffles of the usual type as employed in boilers of the character specified. The location of the baffle section 15 in the bank of tubes 7 involves 50 an advantage, as the portions of the tubes to the right of the section, are thus exposed to and receive the full benefit of the radiant or reflected heat from the opposite wall 19 of the combustion chamber, while the tubes to the left of this section 55 which are too far in to receive any substantial benefit from the reflected heat from the wall 19, are exposed to, and given the benefit of, the heated gases of combustion 60 as they sweep along and across the tubes in making the turn. The reverse curve of the 65 gases at this point gives a large heat transfer to the water in the tubes 7 at this point. Similarly, the reverse curve of the gases across and along the upper portions of the tubes 5 at the right of the baffle section 17 70 provides for a large heat transfer to the tubes at this point. Other advantages incident to the construction will be readily apparent to those skilled in the art.

What I claim is:

1. In combination in a boiler of the vertical type having a lower drum and three spaced upper drums and three sets or banks of water tubes extending upward from the lower drum to the upper drums, a fire-box beneath the boiler, an outlet flue or stack at the rear of the boiler, a baffle extending from the lower drum longitudinally of the tubes of the first bank for a portion of their length and then transversely of such tubes and 75 across the middle bank of tubes, and a second baffle extending downwardly from the upper rear drum for a portion of the length of the rear bank of tubes, and then laterally across the lower portion of the middle bank of tubes.
2. In combination in a boiler of the vertical type having a lower drum and three spaced upper drums and three sets of banks of water tubes extending upward from the lower drum to the upper drums, a fire-box beneath the boiler, an outlet flue or stack at the point where the gases leave the tubes, a baffle extending from the lower drum longitudinally of the tubes of the front bank for 80 a portion of their length and then transversely of such tubes and across the middle bank of tubes, and a second baffle extending downwardly from the upper rear drum for a portion of the length of the rear bank of tubes, and then laterally across the lower portion of the middle bank of tubes, the two baffles being located so as to divide the middle bank of tubes into three sections of 85 increasing length from the bottom section up.
3. In combination in a boiler of the vertical type having a lower drum and three spaced upper drums and three sets or banks of water tubes extending upward from the lower drum to the upper drums, a fire-box beneath the boiler, an outlet flue or stack at a point where the gases leave the tubes, a baffle extending from the lower drum longitudinally of the tubes of the front bank for 90 a portion of their length and then transversely of such tubes and across the middle bank of tubes, and a second baffle extending downwardly from the upper rear drum for a portion of the length of the rear bank of tubes, and then laterally across the lower portion of the middle bank of tubes, the two baffles being located so as to divide the middle bank of tubes into three sections, and the portion 95 of the baffle which extends longitudinally of 100

the front bank of tubes being located inside the passageway, as thus provided, being progressively of decreasing cross sectional area from its entrance end onward.

4. In combination in a boiler of the vertical type having a lower drum and three spaced upper drums and three sets or banks of water tubes extending upward from the lower drum to the three upper drums, an arch and fire-box, and baffles for directing the gases of combustion, first, clear across the upper portions of both the front and middle banks of tubes, and into the rear bank, second, backwardly across the upper portion of the rear bank of tubes, across the entire center bank of tubes and into the lower portion of the tubes of the first bank, and third, turning in the lower part of the tubes of the front bank forwardly across the lower portions of the middle and rear banks of tubes and to the stack.
5. In combination in a boiler of the vertical type having a lower drum and a plurality of spaced upper drums and a set or bank of water tubes extending upward from the lower drum to each of the upper drums, a fire box beneath the boiler, an outlet flue or stack at the point where the gases leave the tubes, a baffle extending from the lower drum longitudinally of the tubes of the front bank for a portion of their length and then transversely of such tubes and across the middle bank of tubes, and a second baffle extending downwardly from the upper rear drum for a portion of the length of such rear bank of tubes, and then laterally across the lower portion of the middle bank of tubes, the two baffles being located so as to divide the middle bank of tubes into three sections of gradually decreasing length from top to bottom, and the passageway, as provided by the baffles, being progressively of decreasing cross sectional area from its entrance end onward, in order to compensate for the shrinkage of the gases due to their decrease in temperature, and to provide for an increasing velocity of the gases as they progress through the various passes of the boiler.

In testimony whereof, I have hereunto subscribed my name this fifth day of May, 1926.

ALFRED C. DANKS.
